4 Claims. (Cl. 333—95)

The present invention relates generally to the microwave art, and, more particularly, to a device for the twisting or rotation of the polarization direction of the waves in a waveguide.

It is already known that in waveguides with a rectangular cross section the rotation of the polarization direction of the waves is obtained by twisting or turning the waveguide in spiral fashion about its longitudinal axis.

It is furthermore known that the same result can be obtained by certain combinations of bends or elbows. But in that case the input and output of the arrangement are displaced parallel to each other and the space requirement is considerably higher.

Recently, a corrugated waveguide with an oval or elliptical cross section has been invented as a structural element, which can be positioned easily due to its high flexibility. Because of its flexible quality it does not require the use of elbows or similar expensive and heavy elements.

If turning of the polarization of the waves in a waveguide is required, then first there must be a change from the flexible corrugated waveguide to a rectangular cross section via a transition or connecting piece. Only then can the turning or twisting of the polarization direction be performed in the conventional way by a rectangular waveguide twisted about its longitudinal axis. This entails a considerable expenditure. One solution is to twist the corrugated waveguide about its longitudinal axis and fix it in the desired position. However, a significant number of tests have shown that the later twisting of the waveguide about its longitudinal axis requires such a large force, that it can not, with a tolerable expenditure, be fixed in this position. Besides this, there is usually a separate short twist incorporated into the waveguide which, for example, is 90°. If the above-mentioned waveguide was deformed later (at the site where it is to be used) this would lead to its destruction or the cross section would be deformed so irregularly that fault-free transmission of electromagnetic waves becomes impossible. Furthermore, the machines necessary to perform this operation are not available at the location where the waveguide is to be used. By the invention however it becomes possible to have a waveguide arrangement with twisted sections undivided by flanges and without the necessity of adapters from oval or elliptical to rectangular cross sections.

With this in mind, it is a main object of the present invention to provide a corrugated waveguide having an oval or elliptical cross section which is twisted spirally about its longitudinal axis by a certain angle per unit length.

Another object of the invention is to provide a device of the character described by means of which turning of the polarization direction can be performed and the waveguide for accomplishing this can be simply and quickly mounted.

A further object is to provide a waveguide arrangement including sections for turning the polarization direction and in which the reflection factors are decreased and the permissible production tolerances are increased in comparison to known devices.

These objects and others ancillary thereto are accomplished in accordance with preferred embodiments of the invention wherein a corrugated elliptical waveguide is

2

fabricated having a uniformly angularly varying major axis so that it is twisted spirally about its longitudinal axis by a predetermined angle per unit of length.

Additional objects and advantages of the present invention will become apparent upon consideration of the following description when taken in conjunction with the accompanying drawings in which:

FIGURE 1 is a schematic elevational view of a corrugated elliptical waveguide made in accordance with the present invention.

FIGURES 2a, 2b and 2c are schematic sectional views taken generally along the planes defined by reference lines a—a, b—b and c—c, respectively, of FIGURE 1. In the shown example the twist angle is constant.

FIGS. 3 and 4 show schematically a waveguide which is twisted in the first section in one direction, in the second section untwisted and in the third section twisted in the opposite direction. The untwisted section can be of any length. The twist angles of the first and last section are independent of each other.

With more particular reference to the drawings, FIGURE 1 shows a corrugated waveguide provided in accordance with the present invention. The elliptical waveguide 1 is provided with the corrugations 2. On the left-hand side of the device shown, the waveguide can be protected against corrosion and mechanical damage by a wear resistant plastic coat 5.

In the plane designated by a—a, the major axis of the elliptically-shaped waveguide is positioned to be what may be considered vertical, as indicated in the corresponding FIGURE 2a. In a further and intermediate plane b—b, the major axis is already turned or twisted e.g. by 45° (see FIGURE 2b) compared to the position it has in plane a—a as shown in FIGURE 2a and this is accomplished by twisting the waveguide about its longitudinal axis. In the plane c—c at the end of the arrangement shown in FIGURE 1, the above-mentioned major axis of the waveguide cross section is turned e.g. by another 45° compared to the cross section along plane b—b, as can be seen from FIGURE 2c. The assembling part, that is between the two cross sections a—a and c—c consequently represents a so-called waveguide "Twister."

The twist angle can be constant for the whole length of the waveguide or can change in a predetermined manner over the length as described above.

The present invention makes it possible to better utilize the advantages of the flexible corrugated waveguide especially because the described deformation of the structural element is performed when it is produced so that besides saving the additional expensive elements described above, a simple and quick mounting is obtained. The use of only one element leads furthermore to a decrease of the reflection factors and larger tolerances in the production of this structural element, which are equally advantageous.

The required "Twist" can preferably be placed at the end of a length of waveguide which is ordered and this can be done by a suitably developed machine which produces the hollow conductor. The twist can, however, be disposed at any desired place within the entire waveguide length which is manufactured of one piece. The point of use and therefore the required length of the waveguide are known. It is therefore possible to produce the complete waveguide length "custom made" and to obtain an optimum of transmitting bandwidth with a minimum of reflections, which is of great importance for radar and radio devices. In the case of military devices the use of an antenna supply waveguide with a "twist" fixed, for example, at the end of this waveguide, saves a considerable amount of time, compared to the conventional art, when constructing a radio communications device.

In a mobile device for example the polarisation direction of transmitter and antenna waveguide are known and

the mounting of the waveguide is known at several points, too. For using the possibility of minor bending radius by bending in parallel to the major axis and for getting the waveguide on both ends with wanted polarisation direction such a waveguide arrangement has to incorporate normally one or several twists. Since today it is necessary to use rigid twists which divide the waveguide arrangement in several flange-coupled sections, winding up the whole waveguide on a drum is impossible. However twists according to the invention are flexible, are derived from the untwisted flexible waveguide and integral with this waveguide. There is no source of unwanted reflexions and the whole arrangement easily can be wound on a reel. Also in the case of separate flexible twists according to the invention inserted with flanges in the waveguide arrangement there is the possibility of winding on a reel. These twists may be cut preferably from a continuously twisted waveguide.

It will be understood that the above description of the present invention is susceptible to various modifications, changes, and adaptations, and the same are intended to be comprehended within the meaning and range of equivalents of the appended claims.

What is claimed is:

1. A device for the twisting of the polarization direction of the waves in a waveguide comprising a corrugated elliptical waveguide which, in its unstressed state, has a cross section which is twisted by a substantial amount

about the longitudinal axis of said waveguide by a predetermined angle per unit of length.

5 2. A waveguide device comprising a length of corrugated hollow conductor material which is elliptical in cross section, the cross section of said conductor when said conductor is in its unstressed state, being twisted, by a substantial amount about the longitudinal axis of said conductor by a predetermined angle per unit of length.

10 3. A waveguide device comprising a length of corrugated hollow conductor material forming a waveguide and which is elliptical in cross section, the major axis of the ellipse, when said waveguide is in its unstressed state, turning by a substantial amount about the longitudinal axis of said waveguide by a predetermined angle per unit of length.

15 4. A device as defined in claim 3 wherein the turning of the major axis of the ellipse is continuous and uniform.
